Edwin R. Cahoon,

BY Drake & Co. ATT'YS.

UNITED STATES PATENT OFFICE.

EDWIN R. CAHOONE, OF NEWARK, NEW JERSEY.

HARNESS-MOUNTING.

SPECIFICATION forming part of Letters Patent No. 361,811, dated April 26, 1887.

Application filed January 4, 1887. Serial No. 223,347. (No model.)

To all whom it may concern:

Be it known that I, EDWIN R. CAHOONE, a citizen of the United States, residing at Newark, in the county of Essex and State of New Jersey, have invented certain new and useful Improvements in Harness-Mountings; and I do hereby declare the following to be a full, clear, and exact description of the invention, such as will enable others skilled in the art to 10 which it appertains to make and use the same, reference being had to the accompanying drawings, and to letters of reference marked hereon, which form a part of this specification.

The object of this invention is to enable a 15 partial covering of hard rubber or similar soft or plastic matter capable of being perforated to be more easily and perfectly applied to the exterior of a metal surface and to supply a harness-mounting devoid of certain defects of 20 ornamentation hereinafter particularized.

Heretofore in the manufacture of harness-mountings and other articles applied material has in some cases been anchored to the casting by means of undercuts or perforations 25 formed in or through the casting, into which the plastic matter has been forced and held to said casting. By this method it has been impossible to secure at the edges of the mountings a neat finish, the edges of the plastic matter near the ends of the mountings 30 extending across the edge face of the body metal so as to interrupt a continuous metal surface. In other cases, especially in the manufacture of knife-handles, pins have been secured to the body metal, and the plastic material has been forced around small heads of 35 said pins; but by that construction the said material is not held as securely as by the method and means herein described. By the 40 present means a continuous side face of metal is secured, and the extremities of the pins or wires when bent down over the covering, as described hereinafter, give a positive security, such as cannot be practically gained by other 45 methods. By the use of double layers the pins or fasteners may be positively bent into a holding relation and afterward covered, if the same is desired.

Referring to the accompanying drawings, 50 in which like letters indicate corresponding parts in each of the figures, Figure 1 illus-

trates a mounting in side elevation prior to applying the finishing cover. Fig. 2 is a sectional view on an enlarged scale through line X, showing the casting with a first application 55 of plastic matter, which is held in place by peculiarly-constructed fasteners. Fig. 3 is a view similar to the last, but showing a second finishing application. Fig. 4 illustrates the completed mounting.

The invention consists in the improved article or mounting, in the combination and arrangements of parts thereof, and in the process by which the article is effected.

In said drawings, *a* indicates the body portion of a harness-mounting or other article, which may be of any shape or construction, and *b b'* a partial covering for the same, which, contrasting with the metal, gives beauty and finish to the article. Said covering is preferably in a plurality of layers, the under layer, *b*, being first secured to the said body by suitable fasteners—such as pins, rivets, or screws—and preferably by the peculiar fastenings shown in the figures of the drawings, which are of wire soldered to the body metal, and, projecting at right angles from the face thereof, are adapted to be thrust through or into the soft covering material and have their extremities to so project from the said covering 65 as to allow of their being turned down over the face of the plastic layer, and thus hold the covering in place. Over the first application or layer a second finishing-layer is placed, said layers being preferably of rubber or other 70 material, adapted to unite when two layers are brought together, and when thus brought into contact to become intimately connected, so that they become as of one integral piece, covering the ends of the fastener, and giving a peculiarly effective finish. When the layers are of 75 rubber and are united, as described, the said rubber is vulcanized and may be finished in any ordinary manner without any seams or joints being apparent.

It is understood that the layer or layers may be of celluloid or other analogous material.

By providing a plurality of layers adhesively joined, as described, I am enabled to secure peculiar results of ornamentation other than 80 those described, and such as cannot or have not, I believe, been secured by other means.

For instance, I am able to produce at the lateral edges of the mounting stripes in different colors by making the first layer of one color—black, for example—and the outer coating of 5 a suitable color in contrast, as red. Thus the inner coating produces a neat and effective ornamental line between the outer layer and the metal.

The fastening-wires are preferably secured 10 at points on the body-casting between the lateral edges of the same, and thus do not interrupt the continuous extension of color at said lateral edges, or otherwise mar the effect of finish. The said fastenings are preferably of 15 wire, as before intimated, and are bent, as in Figs. 1, 2, and 3, having upwardly-extending arms *c*, which can be turned down, as at *c'*, on the outer face of the body metal. The base portion *c''* of the fastener engages the surface 20 of the fastener, and is preferably soldered thereon.

Having thus fully described my invention, what I claim as new is—

1. The process of manufacturing harness-
mountings and allied articles, which consists, 25 essentially, in securing projecting fasteners on the surface to be covered, applying a plastic layer to said surface, causing the said fasteners to project through said layer, bending the 30 projecting ends of said fasteners upon the surface, and finally applying a second layer to conceal the bent portions of said fasteners, substantially as set forth.

2. The process of manufacturing harness-
mountings and allied articles, which consists, 35 essentially, in securing projecting fasteners on the body metal to be covered, applying a plastic layer to said body metal, and at the same time thrusting the ends of the fastener through said layer and bending said end down over 40 the layer to hold said layer to said surface, substantially as set forth.

3. In combination, in a harness-mounting, a body, *a*, a plastic layer *b*, held by fastening *c*, secured to said body, and a second layer of 45 like material adhesively joined to the first said covering, substantially as set forth.

4. In combination, in a harness-mounting, with a body, *a*, a fastening-wire secured upon the face of said body, thrust through the plastic covering, and bent to hold said covering, and said covering, said parts being arranged and combined substantially as set forth. 50

5. The combination, in a harness-mounting, with a body and layers *b* *b'*, of wire fasteners having a base, an arm, and a turned-down ex- 55 tremity, substantially as set forth.

In testimony whereof I have hereunto set my hand this 24th day of December, 1886.

EDWIN R. CAHOONE.
